UNITED STATES PATENT OFFICE.

THEOPHILUS P. WEIDLER, OF GLENOLA, PENNSYLVANIA.

CAR-COUPING.

SPECIFICATION forming part of Letters Patent No. 570,652, dated November 3, 1896.

Application filed August 19, 1896. Serial No. 603,184. (No model.)

To all whom it may concern:

Be it known that I, THEOPHILUS P. WEIDLER, a citizen of the United States, residing at Glenola, in the county of Lancaster, State of Pennsylvania, have invented certain Improvements in Car-Couplings, of which the following is a specification.

This invention relates to improvements in automatic car-couplers; and the objects of 10 the invention are, first, to protect the coupling mechanism against undue strain in coupling the cars; second, to maintain the coupling-pin in a vertical position in inserting it in or raising it from the draw-head, 15 and, third, to lock the device for operating the coupling-pin.

The invention consists in the construction and combination of the various parts, as hereinafter fully described, and then pointed 20 out in the claims.

In the accompanying drawings, forming a part of this specification, Figure 1 is a longitudinal vertical section of a draw-head embodying my improvements; Fig. 2, a top 25 plan view of the same, the top of the weight-chamber being cut away; Fig. 3, a front elevation of the draw-head; Fig. 4, a perspective view of the device for locking the shaft through which the coupling-pin is raised; 30 and Fig. 5, a perspective view of a portion of the lever-weight, showing the handhold for raising the same.

Similar letters indicate like parts throughout the several views.

Referring to the details of the drawings, A indicates the front of a car; A', the draw-head; A², the draw-bar; A³, the coupling-pin, and A⁴ the coupling-link.

On the draw-head adjacent to the front of 40 the car-body is a weight-chamber B, formed by vertical walls B', and having a lid B² closing the top, through which a weighted lever, to be described, is inserted. In the forward portion of the bottom of chamber B is a centrally-located slot b longitudinal of the draw-head and extending beyond the front wall of 45 said chamber to form the usual opening b' for the coupling-pin A³. On the bottom of the draw-head are two parallel vertical ribs or walls D longitudinal of the draw-head and forming between them a groove d, that lies beneath and ranges with slot b. Ribs or walls D extend from beneath the coupling-pin opening, b', back toward the rear of the

draw-head, and, if preferable, they may extend in height from the bottom plate to the top plate of the draw-head, as shown by broken lines d', Figs. 1 and 3. The front ends or shoulders of these ribs or walls are rounded or beveled, as shown at d², to receive the end of link A⁴ when the same is to be engaged by the coupling-pin.

E indicates a weight or block situated in chamber B and oblong in outline longitudinally of the draw-head. This weight or block 65 is pivoted on a rod E', passing through the lower front part thereof and through the side walls of said chamber. On the center of the bottom of said front part is a tongue F, passing down through slot b and having a heel 70 F' on the lower end thereof engaging groove d, the front edge of which is beveled, as shown at f, and on the front of tongue F is a forwardly-projecting lip f', located about on a line with or a little below the top plate a of 75 the draw-head. In the normal position of the lever formed by weight E and tongue F lip f' extends beneath the coupling-pin opening and supports said pin in an elevated position, as shown in Fig. 1, the rear end e of weight E 80 resting upon the portion e' of the bottom of chamber B, closing that end of slot b, thus limiting the forward movement of tongue F. The weight and its attachments are raised from chamber B by a handhold e², located in 85 a recess e³ in the top thereof.

In operating, the coupling-pin being elevated and supported by lip f', the coupling-link entering the draw-head engages the front and beveled edge f of tongue F and pushes 90 the same back, so as to remove lip f' from beneath the coupling-pin and permit it to engage the link. In thus inserting the coupling-link in the draw-head its inner movement is limited by shoulders d² of ribs or walls D, 95 so that weight E is not raised more than is necessary to clear lip f' from beneath the coupling-pin. When said pin is again raised, the weight E, by reason of its size, acting through tongue F, ejects the coupling-link 100 from the draw-head.

Locating the weight of the lever E F in a separate chamber above the draw-head permits the use of a larger and heavier weight having greater leverage than those heretofore employed, thus insuring a positive ejection 105 of the coupling-link and at the same time protecting the mechanism from the weather.

G indicates a post set in the front wall of chamber B in rear of the coupling-pin opening and extending above said chamber. In this post is a vertical beveled groove g , that 5 is engaged by a rounded lip a' on the elongated head a^2 of coupling-pin A³. In front of the coupling-pin opening is another post, G', the inner edges of which are beveled; and this post G' engages a groove in the front of 10 the head a^2 of the coupling-pin. The head of the coupling-pin extends beyond the periphery thereof on all sides, so that when it is closed the pin-opening in the draw-head is 15 closed, and vertical movement of said pin is insured by the engagement of the head thereof with the posts G and G', as has been described.

H indicates a rock-shaft extending inward from the side of the car to the center of the end thereof, said shaft having its bearings in 20 staples h , secured in said front of the car. On the inner end of the rock-shaft there is a stud h' , and from the stud there branch forward two curved arms H', the outer ends, h^2 , whereof extend forward in parallel lines. To 25 these ends are attached the ends of a slack chain I, that passes through a ring I' on the upper end of the coupling-pin.

On the outer end of rock-shaft H is a locking-head, L, rectangular in outline and of 30 greater depth than width, and beneath head L is a projection M on the end of the car, having therein a socket m, adapted to receive head L when in an upright position. When arms H' h^2 are extended in a horizontal position, as shown in full lines in Figs. 1, 2, and 35 3, head L is engaged with socket m and rock-shaft H is prevented from revolving; but when it is desired to disengage the coupling-pin from the interior of the draw-head, head 40 L is raised from socket m by handle M', as shown by broken lines m', Fig. 4, and the rock-shaft is then turned in its bearings so as to throw arms H' h^2 upward into the position illustrated by broken lines m², Fig. 3.

Having thus described my invention, what 45 I claim as new, and desire to secure by Letters Patent, is—

1. The combination, in a draw-head, of a chamber on the draw-head, having a slot in 50 the bottom thereof, a weighted lever-arm having its front end fulcrumed in said chamber, a bearing back of said slot, adapted to limit the downward movement of said lever-arm, and a tongue on the front of said lever-arm 55 and projecting down into the draw-head and constructed to support the coupling-pin in an elevated position, the tongue projecting across the line of travel of the coupling-link, for the purpose specified.

60 2. The combination, in a draw-head, of a chamber on the draw-head, having a slot in the bottom thereof, a weighted lever-arm having its front end fulcrumed in said chamber, a bearing back of said slot, adapted to limit 65 the downward movement of said lever-arm, a tongue on the front of said lever-arm and projecting down into the draw-head, a lip on

the tongue, adapted to project beneath the coupling - pin opening, the portion of the tongue below said lip projecting across the 70 line of travel of the coupling-link, for the purpose specified.

3. The combination, in a draw-head, of a chamber on the draw-head, having a slot in the bottom thereof, a weighted lever-arm piv- 75 oted in said chamber, ribs on the bottom of the draw-head and forming a groove ranging with the slot in the bottom of the chamber, said ribs lying in the path of travel of the coupling-pin, and a tongue on the lever-arm, 80 extending down through said slot into said groove, said tongue being constructed to support the coupling-pin in an elevated position, for the purpose specified.

4. The combination, in a draw-head, of a 85 chamber on the draw-head, having a slot in the bottom thereof, a weighted lever-arm hav- ing its front end fulcrumed in said chamber, a bearing back of said slot, adapted to limit the downward movement of said lever-arm, 90 ribs on the bottom of the draw-head and form- ing a groove ranging with the slot in the bot- tom of the chamber, said ribs lying in the path of travel of the coupling-link, and a tongue on the front of the lever-arm and ex- 95 tends down through said slot into said groove, said tongue being constructed to sup- port the coupling-pin in an elevated position, for the purpose specified.

5. The combination, in a draw-head, of a 100 chamber on the draw-head, having a slot in the bottom thereof, a weighted lever-arm hav- ing its front end fulcrumed in said chamber, a bearing back of said slot, adapted to limit the downward movement of said lever-arm, 105 ribs on the bottom of the draw-head and form- ing a groove ranging with the slot in the bot- tom of the chamber, said ribs lying in the path of travel of the coupling-link and having their frontends beveled, a tongue on the front 110 of the lever-arm and extending down through said slot into said groove, a lip on the tongue, adapted to project beneath the coupling-pin opening, the front edge of the portion of the tongue below the lip being inclined backward 115 from said lip to the lower end thereof, sub- stantially as and for the purpose specified.

6. The combination, in a draw-head, of a post on one side of the coupling-pin opening and having a vertical groove therein, a post 120 on the opposite side of said opening, a coup- ling-pin head having a lip constructed to en- gage the groove in the first post and a groove adapted to embrace the second post, a rock- shaft, outwardly-projecting arms on the rock- 125 shaft, and a slack chain attached to said arms and passing through a ring on the coupling- pin, substantially as and for the purpose speci- fied.
